CLAIM

The ornamental design for a portable electronic device, as shown and described.

DESCRIPTION

FIG. 1 is a front perspective view of a portable electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the same portable electronic device in an alternate position thereof.

The broken lines illustrating portions of the portable electronic device from no part of the claim design.
